(57) **CLAIM**

The ornamental design for an adjustable hinge, as shown and described.

DESCRIPTION

FIG. 1 is a front elevational view of an adjustable hinge showing my new design.

FIG. 2 is a rear elevational view thereof;

FIG. 3 is a top plan view thereof;

FIG. 4 is a bottom plan view thereof;

FIG. 5 is a left elevational view thereof; and

FIG. 6 is a right elevational view thereof;

FIG. 7 is a rear, left perspective view thereof; and,

FIG. 8 is a front, right perspective view thereof.

The broken lines in the drawing depict portions of the adjustable hinge that form no part of the claimed design.
